CONTINUOUS TUNNEL KILN AND METHOD
OF OPERATING THE SAMEPhilip d'Huc Dressler, Pittsburgh, Pa., assignor
to Swindell Dressler Corporation, Pittsburgh,
Pa., a corporation of Pennsylvania

Application September 4, 1931, Serial No. 561,119

5 Claims. (Cl. 263—28)

My present invention relates to continuous tunnel kilns, and particularly to open fire kilns in which the gaseous products of combustion of the fuel used in heating the kiln pass into the goods space of the kiln from combustion chambers in which the combustion of the fuel is initiated and wholly or largely completed.

My present invention consists in improvements in kiln structure and arrangement, and in methods of kiln operation, devised with the general object in view of securing a desirable heat distribution in the kiln goods space, and particularly in the main heating section of said space, and of modifying said distribution as conditions make desirable, with a kiln structure and heating means which are desirably simple, effective, relatively inexpensive and durable, and which permit of a rapid rate of supply of heat to the heating portion of the kiln, and hence of high capacity kiln operation without subjecting the goods or goods containers to the direct impingement of high temperature heating gases moving at high velocity, or otherwise subjecting the goods or the kiln structure to injurious local overheating.

In accordance with the present invention, I employ combustion chambers which are distributed along the sides of the heating zone of the kiln as has been customary, but which differ from those heretofore employed in that they are arranged to pass heating gases into the goods space adjacent both the top and bottom of the latter, but which do not pass heating gases directly into contact with the sides of the masses or stacks of goods moving through the goods space of the kiln. In the preferred embodiments of the present invention the heating gases pass into the kiln goods space from the combustion chambers through combustion chamber wall ports distributed along the lengths of the combustion chambers in upper and lower sets.

In accordance with the present invention, the heating gas discharge rates through the different ports are proportioned to insure proper relative amounts of heating gas flow into the top and bottom portions of the goods space, and also into the different longitudinal portions of the goods space of the kiln. Such proportioning may well be secured, and varied as conditions make desirable, in part by the dimensions initially given the ports, and in part by the use of adjustable throttling dampers or obturators associated with some or all of the ports. In practice, I have found that in some kilns at least, the desired distribution can be secured by means of adjustable throttling dampers associated with one set only of

the above mentioned upper and lower sets of combustion chamber outlet ports. With only the outlet ports of one set provided with dampers, it is readily possible, of course, to vary the relative amounts of heating gases discharged through the upper and lower sets of ports, and I have also found that by the adjustment of the dampers of one set only, and by the regulation of the fuel supply to the different combustion chambers, an adequate variation of the total inflow of heating gas into different longitudinal portions of the goods space may be secured.

Heretofore it has been proposed to discharge heating gases into the goods space of open fire kilns either wholly at the bottom or wholly at the top of the goods space, and it has also been proposed to discharge the heating gases into the goods space through ports distributed, both horizontally and vertically, along the sides of said space. I have found, however, that none of the methods of introducing the heating gases just mentioned, will give satisfactory kiln heating at least for many of the purposes for which said kilns are used. When all the heating gases are introduced into the goods space at the bottom of the latter, there is ordinarily a pronounced and objectionable tendency to overheat the goods in the lower portion of the goods space. When all the heating gases are introduced into the goods space adjacent the top of the latter, local overheating of the goods in the upper portion of the goods space is inevitable. When any considerable portion of the heating gases directly enter the goods space at the sides of the latter, local overheating of the goods at the sides of the goods space is inevitable.

Local overheating of the goods in any portion of the goods space is always objectionable. With many classes of goods, it results in the production of a considerable amount of imperfect second grade or useless goods. Local overheating of the goods at the sides of the goods space is particularly objectionable in the case of coarse clay products such as paving brick, which even though not directly injured by the overheating, are thereby subjected to unequal shrinkage which not only prevents uniformity in finished brick dimensions and shapes, but tends to displace the bricks stacked on the cars. Such displacement may and occasionally does result in injury to the kiln structure and cars which delay and add to the expense of kiln operation.

Under ordinary practical conditions of kiln operation, the relative heating requirements of different portions of the goods space vary from

time to time as a result of changes in the character of the goods fired, changes in the rate at which goods are moved through the kiln, and of other causes, and my present invention is therefore of especial value because it makes possible easy and accurate variations in the distribution of the heating gases passing to different portions of the goods space as conditions may require.

In accordance with the present invention, I also make use in some cases of provisions for effecting a local recirculation of the kiln atmosphere by drawing gas from the goods space into the combustion chamber, mixing it with the products of combustion formed therein and discharging the mixture into the goods space through the combustion chamber outlets. This procedure, in addition to effecting a local longitudinal circulation of the goods space atmosphere, highly desirable of itself in some cases, effects a reduction in the maximum combustion chamber temperature, thereby reducing the liability to local overheating of the kiln structure and local overheating of the goods, the latter being of especial importance in metal annealing and other kilns in which the maximum goods space temperature is relatively low.

The general features of the present invention may be used with advantage in kilns employed for a wide variety of purposes and requiring very different goods space temperature conditions, and without regard to the character of the fuel used, which may be a rich gas such as natural gas, a lean gas such as producer gas, oil, or coal, as conditions make desirable.

The various features of novelty which characterize my invention are pointed out with particularity in the claims annexed to and forming a part of this specification. For a better understanding of the invention, however, its characteristics, advantages and specific objects attained with its use, reference should be had to the accompanying drawings and descriptive matter, in which I have illustrated and described preferred embodiments of the present invention.

45 Of the drawings:

Fig. 1 is a somewhat diagrammatic plan view of a tunnel kiln;

Fig. 2 is a partial section on the line 2—2 of Fig. 1, with an inner combustion chamber wall portion broken away to show the kiln car structure;

Fig. 3 is a transverse section on the broken line 3—3 of Fig. 1;

Fig. 3A is a transverse section on the line 55 3A—3A of Fig. 2;

Fig. 4 is a view, generally similar to Fig. 1, of a kiln differing in type from that shown in Fig. 1;

Fig. 5 is a section on the broken line 5—5 of Fig. 4; and

Fig. 6 is a partial horizontal section on the line 6—6 of Fig. 5.

In Figs. 1, 2, 3 and 3A of the drawings, I have illustrated an embodiment of the present invention in a continuous tunnel kiln A especially devised and adapted for use in annealing malleable castings. In the kiln shown in Figs. 1, 2, 3 and 3A, the whole or main heating effect is obtained by the combustion of fluid fuel in combustion chambers B, distributed along a substantial portion of the length of the kiln at each side of the latter. In Fig. 1, A' represents a heating gas outlet connection leading to a chimney or exhaust fan (not shown) which withdraws from the kiln the waste heating gases entering the kiln goods space from said combustion chambers B. The

5 kiln heating effect of the combustion chambers B may, or may not, be supplemented by the heating effect of burners supplying heating gases to the cooling zone section of the kiln, as conditions of operation make desirable. I have not thought it necessary to illustrate such supplemental burners, as their construction and arrangement constitute no part of the present invention and may be in accordance with known prior practice.

10 In the kiln shown in Figs. 1-3, the combustion chambers B are arranged in end to end pairs in side bays or lateral enlargements A² of the kiln chamber, and the burners for the two combustion chambers in each bay are located in, or extend 15 into the opposite end walls of the bay, the adjacent end to end bays being spaced far enough apart to permit ready access to the burners through the space between the adjacent bay ends and at the outer side of the narrower portion of the kiln connecting the bay enlargements of the 20 latter.

25 The combustion chambers B may well take the form of suitably shaped cavities in the main side walls of the kiln structure, but as shown in Figs. 1 to 3A, each combustion chamber comprises inner and outer side walls b' and b², a bottom wall b³, a top wall b⁴ and end walls b⁵, all separate from the main kiln wall and supported on a bench or bottom wall portion A⁴ of the corresponding bay. The formation of the combustion chamber walls 30 separate from the main kiln walls, has the advantage of confining the injurious effects of local combustion chamber overheating to the walls of the combustion chamber, thereby facilitating, and reducing the cost of repairs which may occasionally become necessary as a result of such overheating.

35 The end wall b⁵ of each combustion chamber adjacent the end of the bay containing said chamber, is formed with an inlet b⁶ through which fluid fuel and air for its combustion enter the combustion chamber. In accordance with the present invention the heating gases pass from each combustion chamber into the kiln chamber proper through a set of bottom outlet ports C, 40 and a set of upper outlet ports D suitably distributed along the length of the combustion chamber. As shown the main portion of the inner side wall b' of each combustion chamber is spaced away from the adjacent side of the goods space proper, but is provided with a lateral enlargement b¹⁰ at its lower end, in which the outer end portions of the ports C are formed. Those ports extend into close proximity with the outer ends of, and may advantageously be proportioned and arranged to permit them to register with, the usual horizontal heating gas channels E' formed immediately beneath the goods supporting platforms E² of kiln cars E which run on the kiln track rails a, and collectively form a movable hearth 50 for transporting goods through the kiln.

55 The upper combustion chamber outlet ports D are shown as extending vertically through each combustion chamber top wall b⁴. The latter is separated from the portion of the kiln crown or roof A⁵ directly above it, by a space through which the heating gases issuing through the ports D pass into the goods space. Conveniently, the top walls b⁴ of the combustion chambers B may be at a level approximately midway between those of the top and bottom of the goods space. A barrier wall b¹¹, which may be in the form of an upward extension of the inner wall b' of each combustion chamber, extends upward from the combustion chamber top wall b⁴ far enough to deflect 70 75

the heating gas streams issuing through the ports D into the goods space adjacent the top of the latter. In consequence the heating gases issuing through the ports D do not directly impinge 5 against the goods at the sides of the goods space, but come into contact with the goods only after their initial velocity has been largely dissipated, and their temperature has been reduced by admixture with the main body of gas in the space 10 directly above the combustion chamber.

As previously explained it is ordinarily desirable to regulate the amount of heating gas discharged through the bottom outlet ports of each combustion chamber relative to the amount 15 discharged through the upper outlet ports by means of dampers or obturators associated with all or some of said outlet ports. In the construction shown in Figs. 1 to 3A, the bottom outlet ports C are not provided with regulating dampers or obturators, but each upper outlet port D is provided 20 with a damper F shown as of the slide brick type. Each damper F may be adjusted as required through a suitably normally closed damper adjustment opening A⁷ formed in the lateral wall of 25 the kiln structure.

In the kiln illustrated in Figs. 1 to 3A oil and air for the combustion of the oil are passed into each combustion chamber B through the burner opening b⁶ in one of its end walls b⁵ by an oil 30 burner G mounted in the corresponding bay end wall. The jet discharge of each burner G enters the interior of the kiln through a nozzle opening A¹⁰ in the corresponding bay end wall. As shown the nozzle opening A¹⁰ is in axial alignment with 35 the corresponding combustion chamber inlet opening b⁶, and the walls in which those openings are formed are spaced apart, thus providing a small chamber H between those walls. Between each chamber H and the goods space of the kiln is a 40 wall b¹⁵ which may be formed by an end extension of the inner wall b' of the corresponding combustion chamber. Each chamber H communicates with the goods space of the kiln through a bottom port H' in the wall b¹⁵, and may communicate 45 with said space through a port H² at its upper end. Advantageously and as shown, the extent of such communication through the upper end of each chamber may be controlled by the adjustment of a corresponding damper h which is adjustable through an adjustment opening A¹¹ 50 formed in the corresponding bay end wall.

With the arrangement illustrated in Figs. 1, 2 and 3, the fuel and air jet discharge from each burner G passes across the corresponding chamber H at the outlet end of the nozzle opening A¹⁰ into the combustion chamber opening b⁶, and by its aspirating action draws gas through the chamber H and into the combustion chamber B from the goods space of the kiln. The amount 55 of gas thus drawn into each combustion chamber B through the associated chamber H may be regulated by adjustment of the corresponding damper h. The recirculation gas flow from the goods space of the kiln through the chambers H 60 into the combustion chambers B and thence back into the goods space through the ports C and D, creates a local longitudinal circulation of the kiln atmosphere which assists materially in obtaining the desired heat distribution in some cases and 65 which always reduces both the maximum and the average combustion chamber temperatures. Such temperature reduction reduces the risk of local overheating of the kiln structure, and by 70 reducing the temperature of the gas jets discharged through the ports C and D, reduces the 75

tendency to local overheating of the goods, a matter of especial importance in a kiln such as a metal annealing kiln in which the maximum goods temperature is relatively low.

Where the local kiln temperature circulation and combustion chamber reducing actions of the chambers H are not required, the chambers H may nevertheless be employed with advantage in some cases, in effecting the introduction of highly heated air for combustion into the combustion 10 chambers B by the aspirating action of such burners as are disclosed and claimed in my prior Patent 1,744,453, granted January 21, 1930. For such use each chamber H is sealed against direct communication with the immediately adjacent 15 portion of the kiln goods space and may be supplied with highly heated air from the kiln cooling space or spaces through suitable connections. Such connections need not be illustrated and described herein, as they may be exactly similar 20 to those disclosed in my said prior patent for supplying hot air to the aspirating burners of said patent.

In the particular arrangement shown in Figs. 1 to 3A, malleable castings to be annealed or 25 other goods to be heated are held in pots e stacked on the work supporting platforms E² of the goods cars E. The bricks or tiles E³ forming the portion of the refractory car superstructure of each car E immediately below its work supporting 30 platform E² are arranged to form the side and bottom walls of the heating gas channels E'. The latter extend from one side to the other of the car and are open at their ends. Refractory slabs E² form the goods supporting platform of the car, and 35 also cover the major portions of its channels E'. Through the uncovered portions of the channels E' the heating gases entering the latter from the ports C may pass upward into the goods space of the kiln at the sides of the pots e. The usual 40 sand seal provisions E⁴ prevent gas flow between the goods space proper, and the space beneath the hearth formed by the car bodies. Suitable sand seal inspection openings A⁸ are formed in the side walls of the kiln structure. 45

The general operation of the kiln shown in Figs. 1 to 3A will be readily apparent to those skilled in the art. As the goods on any particular kiln car E move progressively through the kiln preheating section A²⁰, through the main heating section in which the combustion chambers B are located, and through the cooling zone A³⁰ of the kiln, the temperature of the goods is raised more or less gradually to its maximum value, and is subsequently reduced more or less in accordance 55 with the heat cycle or treatment to which the goods are to be subjected.

The amount of heat supplied by each combustion chamber B can be increased or decreased by adjustment of the corresponding burner G. The 60 distribution of heat to the goods space from each combustion chamber may be varied as conditions require, both longitudinally of the kiln and in a vertical direction, by suitable manipulation of the dampers F associated with the upper outlet 65 ports D. The heat distribution is also subject to regulation by adjustment of the different dampers h. The adjustment of the dampers h varies the local longitudinal flow of the goods space atmosphere produced by the aspirating effect of the 70 burners G on the gas entering the chambers H, and also varies the heat distribution in the goods space somewhat by varying the relative inflows into the chambers H through the upper ends of the latter and through the ports H'. 75

By the conjoint use of the various heat distribution controlling devices the temperature conditions in different portions of the main heating zone section of the goods space can be closely regulated as conditions of operation make necessary or desirable. The actual temperature conditions existing are determinable in the usual way, of course, by means of suitably disposed pyrometers I. As has been previously explained in detail, the recirculation produced by the aspirating action of the burners G on the gas in the chambers H reduces the combustion chamber temperatures and minimizes the liability to local overheating of the combustion chambers and the goods.

While the particular kiln structure shown in Figs. 1 to 3A was especially designed, for use in metal annealing operations in which the maximum goods space temperature is relatively low, the general features of the present invention are not restricted to use in annealing kilns, or in kilns in which the maximum goods space temperature is relatively low, or in kilns heated by the combustion of fluid fuel, and in Figs. 4, 5 and 6 I have illustrated by way of example the use of general features of the present invention in a kiln AA suitable for use in firing paving brick, and in which the maximum kiln temperature is much higher than in an annealing kiln, and in which the sole or main heating action results from the combustion of coal burned on grates.

The kiln AA is in many respects like the kiln A, and some of the parts of the two kilns which do not differ significantly from one another are designated by the same reference letters. The main heating zone portion of the kiln AA is of uniform width, but to accommodate the combustion chambers BB mounted therein is made wider than the kiln preheating and cooling zone section A²⁰ and A³⁰ respectively. The latter may be generally similar in form to the combustion chambers B of Figs. 1, 2 and 3, and, as shown, comprise inner and outer walls bb', bb², a top wall bb⁴ and end walls bb⁵, generally similar to the walls b', b², b⁴ and b⁵, respectively, of the combustion chambers B. The walls bb' and bb⁴ are formed with ports C and D, respectively, and the wall bb' is extended upwardly to form a barrier b¹¹ like that shown in Figs. 1 to 3A. With the construction shown in Figs. 4, 5 and 6, however, the combustion chambers BB do not receive fluid fuel through burner ports in their end walls. On the contrary, each combustion chamber BB is shown as receiving burning gases at a point midway between its ends through a port b²⁰ in its outer wall bb², from the fire box K' of a corresponding furnace chamber K which projects laterally outward from the lower portion of the side wall of the kiln structure.

As shown, each furnace K is provided with a grate K²⁰ between its fire box K' and subjacent ashpit K². The fuel bed on each furnace grate may be trimmed and replenished by hand firing through a doorway K³ in the outer wall of the furnace. Ordinarily, however, coal is fed to each fire box by a suitable stoker L associated with the corresponding furnace. The fire box K' of each furnace K and the associated combustion chamber BB are in direct communication through the corresponding port b²⁰, and each combustion chamber BB is in effect an extension of the combustion chamber or fire box of the corresponding furnace K. Air for combustion is supplied to the ashpit K² of each furnace through an inlet K⁴ which may be connected to the outlet of a blower.

The wall bb' of each combustion chamber B is shown as differing significantly from the corresponding wall b' of Figs. 1 to 3A, only in having a thickened imperforate central portion bb¹¹ which is in line with the port b²⁰ and is formed with oppositely inclined surfaces facing said port. This thickened portion bb¹¹ of the wall bb' provides a suitable flame impact surface and deflects the burning and unburnt gases entering the combustion chamber BB toward the opposite ends of the latter. As no ports C are formed in the wall portion bb¹¹, the latter prevents the gases from entering the kiln goods space incompletely burned and at high velocity as they may enter the combustion chamber BB through the port b²⁰ from the fire box K'.

By the discharge of the heating gases in the goods space of the kiln in suitably proportioned amounts through the lower and upper sets of ports C and D provided in each of the kilns, the same general advantages are obtained with the kiln AA of Figs. 4, 5 and 6, as with the kiln shown in Figs. 1 to 3A.

While in accordance with the provisions of the statutes, I have illustrated and described the best forms of my invention now known to me, it will be apparent to those skilled in the art that changes may be made in the forms of the apparatus and methods disclosed without departing from the spirit of my invention as set forth in the appended claims, and that certain features of my invention may sometimes be used to advantage without a corresponding use of other features.

Having now described my invention what I claim as new and desire to secure by Letters Patent, is:

1. The improved method of operating an open fire continuous tunnel kiln comprising a plurality of combustion chambers distributed along the length of the kiln goods space each of which discharges heating gases into said space, which consists in mixing products of combustion formed in each combustion chamber with gas passed into the latter from the adjacent portion of the goods space, in such manner that the temperature of the heating gases passing from each combustion chamber into the goods space is reduced and a local longitudinal circulation of the goods space atmosphere is effected, and varying the amounts of gas so passed into the different combustion chambers to thereby vary the heat distribution in the goods space.

2. The combination in an open fire continuous tunnel kiln of combustion chambers at the sides of the kiln goods space each of which discharges heating gases into said space, burner means discharging fluid fuel jets into the combustion chambers, and means associated with said burner means for passing gas from the goods space of the kiln into contact with said jets whereby the aspirating action of the latter moves said gas into the combustion chambers.

3. The combination in an open fire continuous tunnel kiln of a combustion chamber at the sides of the kiln goods space and discharging heating gases into said space having a burner inlet which is in communication at its outer end with the kiln goods space, and means for discharging a fluid fuel jet into said chamber through said inlet and thereby returning gas from the goods space into the combustion chamber by the aspirating action of said jet.

4. The combination in a continuous tunnel kiln comprising alternate narrow and wide portions, of combustion chambers located in said wide por-

tions, and a fluid fuel burner for each combustion chamber located in a transverse wall of the corresponding wide portion of the kiln, the adjacent end wall of the combustion chamber being formed with a burner inlet opening through which said burner discharges a fuel jet into the chamber and being separated from said transverse wall by a space communicating with the goods space of the kiln and across which said fluid fuel burner draws gas from the goods space into the combustion chamber by its aspirating action.

5. The combination in a continuous tunnel kiln comprising alternate narrow and wide portions,

of combustion chambers located in said wide portions, and a fluid fuel burner for each combustion chamber located in a transverse wall of the corresponding wide portion of the kiln, the adjacent end wall of the combustion chamber being formed with a burner inlet opening through which said burner discharges a fuel jet into the chamber and being separated from said transverse wall by a space communicating with the goods space of the kiln and across which said fluid fuel burner draws 10 gas from the goods space into the combustion chamber by its aspirating action.

PHILIP D'HUC DRESSLER.
